(57) **CLAIM**

We claim the ornamental design for an electronic cigarette vaporizer, as shown and described.

DESCRIPTION

FIG. 1 is a perspective view of an electronic cigarette vaporizer according to an embodiment.

FIG. 2 is a front view of the electronic cigarette vaporizer depicted in FIG. 1.

FIG. 3 is a back view of the electronic cigarette vaporizer depicted in FIG. 1.

FIG. 4 is a right side view of the electronic cigarette vaporizer depicted in FIG. 1.

FIG. 5 is a left side view of the electronic cigarette vaporizer depicted in FIG. 1.

FIG. 6 is a top view of the electronic cigarette vaporizer depicted in FIG. 1; and,

FIG. 7 is a bottom view of the electronic cigarette vaporizer depicted in FIG. 1.

In the drawings, the broken lines depict environmental subject matter only and form no part of the claimed design.
